UNITED STATES PATENT OFFICE.

PAUL A. CUENOT, OF HARRISBURG, PENNSYLVANIA.

CRUCIBLE-STEEL-MELTING FURNACE.

Application filed August 8, 1922. Serial No. 580,387.

To all whom it may concern:

Be it known that I, PAUL A. CUENOT, a citizen of the United States, residing at Harrisburg, county of Dauphin, State of Pennsylvania, have invented a new and useful Crucible-Steel-Melting Furnace, of which the following is a specification.

My invention relates to a novel construction of a crucible steel melting furnace and a novel method of operation wherein the crucible is located in an enclosing heating chamber and is not disturbed until it has burnt out or lost its usefulness, the molten metal being tapped from the bottom of the crucible and run direct into the ingot mold which is directly under the crucible, whereby the life of the crucible is greatly prolonged and at the same time a better control of the molten metal in the crucible is afforded.

It further consists in a novel manner of positioning the ingot mold with respect to the bottom of the combustion chamber and of a novel construction whereby the molten metal is tapped directly from the bottom of the crucible and run direct into the ingot mold directly under the crucible, said ingot mold being held up against the bottom of the combustion chamber by a hydraulic ram or any other type of hoisting device.

It further consists of a novel ingot mold provided with an outer shell forming a chamber or space around said mold for the reception of compressed air whereby the ingot mold is kept cool so as to freeze the metal as quickly as possible.

It further consists of novel means for exhausting or mechanically withdrawing the gases and heat from the upper portion of the ingot mold by means of a vacuum pump or its equivalent.

It further consists of a novel collocation of hydraulic ram, ingot mold, combustion chamber, crucible and heating chamber therefor, whereby a very compact and efficient structure is produced.

A further object of my invention is to produce a more uniform metal than can now be made in the present method of melting cast steel by the present crucible processes.

It further consists of other novel features of construction and advantage, all as will be hereinafter fully set forth.

For the purpose of illustrating my inven-

tion, I have shown in the accompanying drawings forms thereof which are at present preferred by me, since they will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a vertical sectional view of a crucible steel melting furnace, embodying my invention.

Figure 2 represents a top plan view of Figure 1.

Figure 3 represents a horizontal section on line 3—3 Figure 1.

Figure 4 represents a horizontal section on line 4—4 Figure 1.

Figure 5 represents a horizontal section on line 5—5 Figure 1.

Figure 6 represents a horizontal section on line 6—6 Figure 1.

Similar numerals of reference indicate corresponding parts in the figures.

Referring to the drawings.

1 designates my novel construction of crucible steel melting furnace, the same comprising a suitable supporting frame work or base 2, above which is located the horizontal supporting wall 3 for the base 4 of the combustion chamber 5, which is contained between the inner and outer walls 6 and 7. Upon the walls 6 and 7 is supported the horizontal wall 8, which supports the crucible 9, the latter having a plug 10 in the bottom thereof which keeps the hole at the bottom of the crucible sealed until the metal in the crucible is ready to be tapped.

11 designates a plug or cover over the top 37 of the furnace to enable the crucible 9 to be recharged, and 12 designates a plug that can be readily removed from the cover 11 at any time when it is desired to look into the crucible and also to take out test specimens, when required.

13 designates the rod that is employed to kick out the plug 10 when the molten metal in the crucible 9 is ready to be poured into the ingot mould 14, said rod being provided with a suitable handle at its lower portion. The ingot mould 14 is composed of the annular wall 15 and the loose bot-

2
tom plate 16, said mould being held up against the bottom 4 of the combustion chamber 5 by means of the hydraulic ram 17 which works in the hydraulic cylinder 18, which is provided with the pipe 19 which furnishes the hydraulic pressure for the cylinder 18, and standard construction of ram being employed. The ingot mold 14 is provided with an outside shell 20 which is 5 provided with holes 21 around its base for the reception of compressed air which is discharged into them from the ports or orifices 22 of the circular pipe 23, it being apparent that this cold air impinging upon 10 the outside of the ingot mould uniformly upon all portions thereof and escaping at the upper orifices 24 at the top of the shell 20 will freeze or solidify the molten metal, as rapidly as possible, so as to avoid piping 15 or segregation of the metal in the ingot, said cold air being received in the chamber or space 38 within the shell 20.

25 designates a hole in the wall 7 which permits the ingress of the heating medium 25 from the burner 26, the fuel used being gas or oil. The heating chamber 27 around the crucible 9 is formed within the walls 28, in which is a sight opening 29 to said heating chamber to determine the desired flame, 30 which should be either a reducing flame or complete combustion of the fuel used, the cover 37 being supported upon said walls.

30 designates flues leading from the combustion chamber 5 to the heating chamber 27, the position of said flues being best understood from Figure 3.

31 designates flues leading from the heating chamber to the atmosphere which are best seen in Figure 2. 32 designates a passageway for the molten metal to drop from the crucible 9 into the ingot mould 14 when the plug 10 in alignment with said passageway is kicked out of its position seen in Figure 1 in the crucible, when the metal in 45 said crucible is melted and ready to be poured into the ingot mould.

In order to remove the gases and to dissipate the heat in the ingot mould 14 when metal is being poured from the crucible 50 thereinto, I employ an exhaust fan or a vacuum pump of any suitable or conventional type, and withdraw the heat and gases from the upper portion of the ingot mould through the passage 33 and pipe 34 to the atmosphere, any suitable type of vacuum pump or exhausting device being employed for this purpose which it is unnecessary to describe in detail.

60 The loose plate 16 that the ingot mould sets on is provided at its bottom with grooves 35 which are luted with clay so as to seal the joint between the ingot mould and said plate. The top of the ingot mould that comes in contact with the bottom 4 of 65 the combustion chamber 5 is also luted with

clay as indicated at 36 for the same purpose.

It will be apparent from the foregoing that the crucible 9, the passageway 32 leading therefrom, the ingot mould, and the hydraulic ram are arranged in vertical alignment, so that a very compact and efficient structure is produced and space is greatly economized.

The operation is as follows:—

The plug 11 having been removed from the cover 37, the plug 10 is placed in the position seen in Figure 1 at the bottom of the crucible, being luted with clay. The crucible 9 is then charged with the proper ingredients. The burner 26 is lit and a pyrometer is provided in the heating chamber 27 to determine the heat therein and the pouring temperature of the molten metal. The plug 11 is then placed in position, being luted with clay to make a seal at the joint between the top 37 and said plug. The plug 12 can be removed when desired so as to examine the contents of the crucible and to make tests when desired. The ingot mould 14 with the bottom plate 16 and shell 20 is set upon the ram 17 and pressure is admitted to the cylinder 18 so as to raise the ram and bring the ingot mold up against the bottom 4 of the furnace.

When the metal in the crucible has arrived at the proper melting point or temperature, the rod 13 is put in place and pushed upwardly and the plug 10 is pushed out of its position seen in Figure 1. This allows the molten metal in the crucible to drop into the ingot mould 14 through the passageway 32. The compressed air admitted to the circular pipe 23 cools the metal in the ingot mould as quickly as possible and simultaneously the gases from the ingot mould are exhausted by means of the vacuum pump and the passages 33 and 34. When the ingot has solidified, the ram 17 can be lowered together with the ingot mould 14 and its shell 20 and the ingot can then be taken out.

The operation is repeated and in this way the heating chamber 27 does not get cold as the burner 26 may always be kept in operation being regulated to suit conditions.

It will be seen from the foregoing that my novel furnace will melt steel in a crucible without necessitating any handling of the crucibles thereby prolonging their life, and I am further enabled to get out more heats from each crucible, the molten metal being poured from the bottom of the crucible direct into the ingot mould by the provision of the removable plug 10 positioned at the bottom of the crucible.

It will further be apparent that during its travel from the crucible to the ingot mould through the passageway 32, the molten metal is not exposed to atmospheric or eli-

matic conditions, since the passageway 32 is within and surrounded by the combustion chamber 5.

It will further be apparent in my novel construction of furnace that by providing the ingot mould with an outer shell 20 a cold air chamber 38 is formed, into which cold air can be forced so as effectively to surround and cool the ingot mould, so as to freeze the metal as quickly as possible to avoid segregation and pipe in the ingot, and means are further provided to dissipate the gases and heat from the upper portion of the ingot mould by the vacuum pump or other equivalent exhausting device, so that a more uniform metal is produced by my device than can be made under the present methods of melting cast steel by the present crucible process.

It will be apparent that in accordance with my present invention, I am able by means of a pyrometer to determine not only the temperature in the heating chamber but also if desired the temperature in the crucible itself by inserting the pyrometer in lieu of the testing plug 12.

It will also be apparent that I can charge the crucible 9 with molten metal if desired so that a continuous cycle can be carried out.

Having thus described my invention, what I claim as new and desire to secure by Letters Patent, is:—

1. In a furnace of the character described, a stationary crucible having an outlet at its bottom, a plug for sealing said outlet, a heating chamber surrounding said crucible, an ingot mould in vertical alignment with said crucible, a passageway leading directly from said outlet to said ingot mould, and a combustion chamber surrounding said passageway.

2. In a furnace of the character described, a stationary crucible having an outlet at its bottom, a plug for sealing said outlet, an ingot mould in alignment with said crucible and a passageway leading directly from said outlet to said ingot mould, in combination with means for exhausting gases from said ingot mould.

3. In a furnace of the character described, a stationary crucible having an outlet at its bottom, a plug for sealing said outlet, an ingot mould in alignment with said crucible, and a passageway leading directly from said outlet to said ingot mould, in combination with means for exhausting gases from said ingot mould, and means for cooling the exterior of said ingot mould by the impingement of jets of compressed air thereupon.

4. In a furnace of the character described, a stationary crucible having an outlet at its bottom, a plug for sealing said outlet, a heating chamber surrounding said crucible, an

ingot mould in vertical alignment with said crucible, a passageway leading directly from said outlet to said ingot mould, and a combustion chamber surrounding said passageway, in combination with means for exhausting gases from said ingot mould.

5. In a furnace of the character described, a stationary crucible having an outlet at its bottom, a plug for sealing said outlet, a heating chamber surrounding said crucible, an ingot mould in vertical alignment with said crucible, a passageway leading directly from said outlet to said ingot mould, and a combustion chamber surrounding said passageway, in combination with means for exhausting gases from said ingot mould, and means for cooling the exterior of said ingot mould by the impingement of jets of compressed air thereupon.

6. In a device of the character stated, the combination of a stationary crucible having a hole in its bottom, a plug therefor, an ingot mould below said crucible and in vertical alignment therewith, a vertical passageway leading directly from said crucible to said ingot mould, a closure for the bottom of said ingot mould, means for holding the latter against the bottom of the combustion chamber, an outer shell for said ingot mould having ports peripherally arranged in the bottom thereof, and an annular compressed air pipe surrounding the lower portion of said shell and having discharge orifices in line with said ports for discharging compressed air against the outer periphery of said ingot mould for cooling the latter.

7. In a device of the character stated, the combination of a stationary crucible having a hole in its bottom, a plug therefor, an ingot mould below said crucible and in vertical alignment therewith, a vertical passageway leading directly from said crucible to said ingot mould, a closure for the bottom of said ingot mould, means for holding the latter against the bottom of the combustion chamber, an outer shell for said ingot mould having ports peripherally arranged in the bottom thereof, an annular compressed air pipe surrounding the lower portion of said shell and having discharge orifices in alignment with said port for discharging compressed air against the outer periphery of said ingot mould for cooling the latter, in combination with means for exhausting gases from the upper portion of said ingot mould.

8. In a device of the character stated, a stationary crucible having a hole in its bottom, a plug therefor, an ingot mould below said crucible and in vertical alignment therewith, a vertical passageway leading directly from said crucible to said ingot mould, means for raising and lowering said ingot mould, an annular shell in said ingot

mould and having exhaust ports for compressed air at its upper portion, and inlet ports for compressed air at its lower portion, said inlet ports being circumferentially arranged, and an annular compressed air pipe having orifices aligning with said lower inlet ports for discharging compressed air thereinto.

9. In a device of the character stated, a combustion chamber, means for supplying fuel thereinto, a heating chamber above said combustion chamber, flues connecting said chambers, a stationary crucible supported

on the base of said heating chamber and having a hole in its bottom, a plug therefor, a downwardly extending passageway extending through said combustion chamber and in alignment with said hole, an inclined passage extending through the walls of said combustion chamber, and a rod adapted to be inserted therein for dislodging said plug from said hole.
